(57) **ABSTRACT**

A coil drive device energizes an operation coil to close an electromagnetic contactor. A rectifier outputs, to a power supply line, an input voltage obtained by full-wave rectification of an AC voltage supplied from a main power source. A controller controls on and off of a switching element connected to a power supply line in series with the operation coil. The controller controls a duty ratio that is an on period ratio of the switching element in each switching period in accordance with a value of a parameter calculated from a detected value of the input voltage, in at least a partial period after start of energization of the operation coil in response to a close command for the electromagnetic contactor.

ELECTROMAGNETIC CONTACTOR

TECHNICAL FIELD

The present disclosure relates to an electromagnetic contactor.

BACKGROUND ART

In an electromagnetic contactor, typically, an operation coil that forms an electromagnet is energized to generate attraction force to attract a movable core to a fixed core, whereby contacts come into contact with each other to close an electric circuit.

As a driving device for the operation coil of an electromagnetic contactor, a configuration that performs switching control of a power supply voltage and applies the controlled power supply voltage to the coil is known. For example, WO 2017/159069 (PTL 1) discloses control to reduce the on/off time ratio (duty ratio) in switching control during the holding control after circuit close, compared with during the close circuit control of the operation coil; and control to suppress excessive coil current during the close circuit control, when an electric circuit is closed.

Specifically, in PTL 1, for coil current in the close circuit control, the duty ratio is controlled by PID control computation of a deviation of an actual value (moving average value) from a setting value in accordance with a predetermined change locus of coil current, and the attraction state of the movable core is detected based on this duty ratio. Thus, transition from the close circuit control to the holding control is accurately determined by detecting the attraction state of the movable core without using a position sensor or a timer, so that an excessive magnetic field due to occurrence of excessive coil current is prevented.

CITATION LIST

Patent Literature

PTL 1: WO 2017/159069

SUMMARY OF INVENTION

Technical Problem

However, in PTL 1, fast computation is required to control coil current in accordance with a predetermined change locus. As a result, higher specifications of a controller that performs computation may increase the production cost.

The present disclosure is made in order to solve such a problem. An object of the present disclosure is to suppress excessive coil current during close circuit control of an electromagnetic contactor with simple control that does not require a fast computational process.

Solution to Problem

According to an aspect of the present disclosure, an electromagnetic contactor includes first and second contacts, a mechanism to generate a biasing force for opening the first and second contacts, an operation coil, and a coil drive device. The operation coil generates an electromagnetic force for bringing the first and second contacts into contact with each other against the biasing force. The coil drive device supplies current for generating the electromagnetic force to the operation coil. The coil drive device includes a

2

rectifier, a switching element, a voltage detector, and a controller. The rectifier outputs, to a power supply line, an input voltage obtained by full-wave rectification of an AC voltage supplied from an AC power source. The switching element is connected to the power supply line in series with the operation coil. The voltage detector detects the input voltage. The controller controls on and off of the switching element. The controller controls on and off of the switching element so as to control a duty ratio that is a ratio of an on period of the switching element in a predetermined switching period shorter than one cycle of the AC voltage. Further, the controller controls the duty ratio in accordance with a value of a first parameter indicating a magnitude of the input voltage that is calculated using a detected value of the voltage detector, in at least a partial period after start of energization of the operation coil in response to a close command for the electromagnetic contactor. When a calculation value of the first parameter is larger than a predetermined reference value, the duty ratio is set to a value lower than when the calculation value is equal to or smaller than the reference value.

Advantageous Effects of Invention

According to the present disclosure, simple control, i.e., control of the duty ratio of a switching element to reflect the magnitude of the input voltage, is performed in at least a partial period after start of energization of the operation coil in response to a close command to the electromagnetic contactor, whereby the duty ratio is reduced when the input voltage is large, and excessive coil current is suppressed.

BRIEF DESCRIPTION OF DRAWINGS

FIG. 1 is a conceptual cross-sectional view of an electromagnetic contactor according to the present embodiment.

FIG. 2 is a block diagram illustrating a configuration of a coil drive device of the electromagnetic contactor according to a first embodiment.

FIG. 3 is a conceptual cross-sectional view in a closed state of the electromagnetic contactor shown in FIG. 1.

FIG. 4 is a block diagram illustrating an overall configuration of a controller shown in FIG. 2.

FIG. 5 is a waveform diagram illustrating duty control by the controller.

FIG. 6 is a flowchart illustrating a process related to setting of a duty ratio in duty control of a switching element shown in FIG. 2.

FIG. 7 is a simulation waveform diagram illustrating a first example of close circuit control in accordance with a close circuit command for the electromagnetic contactor.

FIG. 8 is a simulation waveform diagram illustrating a second example of close circuit control in accordance with a close circuit command for the electromagnetic contactor.

FIG. 9 is a conceptual waveform diagram for explaining closed circuit holding control by the coil drive device of the electromagnetic contactor according to the present embodiment.

FIG. 10 is a flowchart illustrating a control process example for performing closed circuit holding control shown in FIG. 9.

FIG. 11 is a block diagram illustrating a configuration of the coil drive device of the electromagnetic contactor according to a second embodiment.

FIG. 12 is a flowchart illustrating a calculation process for an adjustment coefficient by a test device shown in FIG. 11.

FIG. 13 is a conceptual diagram illustrating an example of switching control according to a third embodiment.

FIG. 14 is a conceptual diagram illustrating a distribution of electromagnetic noise intensity by switching control according to the third embodiment.

DESCRIPTION OF EMBODIMENTS

Embodiments of the present disclosure will be described in detail below with reference to the drawings. In the following, like or corresponding parts in the drawings are denoted by like reference signs and a description thereof is basically not repeated.

First Embodiment

FIG. 1 is a conceptual cross-sectional view illustrating a configuration of an electromagnetic contactor according to a first embodiment. FIG. 1 shows a schematic cross-sectional view of an electromagnetic contactor in an open state of an electric circuit (during an open circuit).

Referring to FIG. 1, an electromagnetic contactor 200 includes a coil drive device 100, a coil 110, a fixed core 120, a movable core 130, a spring 140, a fixed terminal 150, a fixed contact 155, a movable terminal 160, and a movable contact 165.

Spring 140 is illustrated as an example of a mechanism for producing biasing force for separating fixed core 120 and movable core 130 (contacts) from each other, that is, biasing force for bringing electromagnetic contactor 200 into an open state.

Coil 110 is wound around a magnetic leg 121 of fixed core 120 and is supplied with coil current I_c by coil drive device 100 to generate an electromagnetic force to attract movable core 130. In the state in FIG. 1, coil current is not supplied and coil 110 does not generate an electromagnetic force. As a result, electromagnetic contactor 200 is in an open state.

Movable terminal 160 is coupled to movable core 130. Thus, when an electromagnetic force generated by coil 110 acts on movable core 130, movable terminal 160 moves integrally with movable core 130.

Fixed contact 155 and movable contact 165 are welded to fixed terminal 150 and movable terminal 160, respectively, at a position opposed to each other during an open circuit shown in FIG. 1.

FIG. 2 is a block diagram illustrating a configuration of the coil drive device of the electromagnetic contactor according to the first embodiment.

Referring to FIG. 2, coil drive device 100 of the electromagnetic contactor according to the first embodiment supplies coil current I_c to coil 110, which is an operation coil of the electromagnetic contactor, with power supply from a main power source 10.

FIG. 3 shows a schematic cross section in a closed state of an electric circuit (during a closed circuit) for the electromagnetic contactor shown in FIG. 1.

Referring to FIG. 3, with supply of coil current, coil 110 generates an electromagnetic force to cause movable core 130 to be attracted toward fixed core 120. When the attraction force (electromagnetic force) generated by coil 110 becomes larger than the biasing force by spring 140, spring 140 is compressed, and movable core 130 is attracted to fixed core 120. Thus, fixed core 120 and movable core 130 come into contact with each other, and fixed contact 155 and movable contact 165 come into contact with each other, whereby electromagnetic contactor 200 is closed. That is, in the electromagnetic contactor shown in FIG. 1 and FIG. 3,

fixed contact 155 and movable contact 165 correspond to an embodiment of "first and second contacts".

The electromagnetic force generated by coil 110 increases with increase of coil current I_c supplied by coil drive device 100. In a state in which fixed core 120 and movable core 130 are separated, coil current is controlled such that the attraction force (electromagnetic force) as described above is generated from coil 110 to close electromagnetic contactor 200. After movable core 130 is attracted to fixed core 120, coil current need to be controlled to generate a necessary electromagnetic force in order to keep the attracted state.

In the close circuit operation of electromagnetic contactor 200, the attraction force acting on movable core 130 is equivalent to the one obtained by subtracting the biasing force by spring 140 from the electromagnetic force generated by coil 110. Therefore, if coil current I_c is excessively large, the attraction force is too large so that impact caused by movable core 130 attracted to fixed core 120 may be excessively large. If this impact damages movable core 130 or movable contact 165, or fixed core 120 or fixed contact 155, the damage may influence the service life of electromagnetic contactor 200. In this way, the control of coil current I_c by coil drive device 100 is important.

Referring to FIG. 2 again, coil drive device 100 includes a rectifier 20, a voltage dividing circuit 25, a control power source 30, a controller 50, a driver 60, a diode 75, a switching element 80, and a current detector 90.

Rectifier 20 is connected to main power source 10 through an operation switch 15. Main power source 10 is, for example, a commercial AC power source and outputs an AC voltage V_{AC} having a predetermined frequency.

Rectifier 20 generates an input voltage V_{in} between a high voltage-side power supply line PL and a low voltage-side power supply line NL by full-wave rectification of AC voltage V_{AC} from main power source 10. For example, rectifier 20 can be configured with a full-bridge circuit of diodes. Low voltage-side power supply line NL usually supplies a ground voltage, and therefore power supply line NL may hereinafter be referred to as ground line NL.

Voltage dividing circuit 25 generates a divided voltage V_{dv} of input voltage V_{in} . Divided voltage V_{dv} has a voltage value obtained by multiplying input voltage V_{in} by a certain voltage dividing ratio (less than 1.0). Control power source 30 converts input voltage V_{in} on power supply line PL into an operating power supply voltage (for example, 5 [V]) of controller 50.

Switching element 80 is connected in series with coil 110 between power supply line PL and ground line NL. Switching element 80 is configured with a semiconductor switching element capable of on/off control in response to an electrical signal input to its control electrode. Switching element 80 is typically a metal-oxide-semiconductor field-effect transistor (MOSFET).

In this configuration, when a positive voltage exceeding a threshold voltage is applied to the control electrode (for example, gate), switching element 80 turns into the on state in which current passes between a high voltage-side electrode (for example, drain) and a low voltage-side electrode (for example, source). Conversely, when the voltage of the control electrode with respect to the low voltage-side electrode (for example, gate-source voltage) is lower than the threshold voltage, switching element 80 turns into the off state in which the high voltage-side electrode is electrically cut off from the low voltage-side electrode.

Diode 75 is connected in parallel with coil 110. In an on period of switching element 80, coil current I_c flows from power supply line PL to ground line NL via coil 110 and

switching element **80**. On the other hand, in an off period of switching element **80**, a circulating current path including coil **110** and diode **75** provides a path of coil current I_c . Current detector **90** is connected in series with coil **110**. Current detector **90** is formed with, for example, a resistor element that produces a voltage drop in accordance with the magnitude of coil current I_c . Alternatively, unlike the illustration in FIG. 2, current detector **90** may be formed with a current sensor such as a Hall element arranged to detect passing current through coil **110**.

Controller **50** may be configured with a microcontroller operating with power supply from control power source **30**. Divided voltage V_{dv} from voltage dividing circuit **25** and a detected voltage V_c from current detector **90** are input to controller **50**. As described above, since detected voltage V_c is proportional to coil current I_c , controller **50** can detect coil current I_c from detected voltage V_c . Controller **50** generates a control signal S_{dv} to control the on/off of switching element **80** by duty control described later.

In the configuration example in FIG. 1, coil **110** corresponds to an embodiment of “operation coil”, voltage dividing circuit **25** corresponds to an embodiment of “voltage detector”, and main power source **10** corresponds to an embodiment of “AC power source”.

FIG. 4 shows a block diagram illustrating an overall configuration of controller **50**.

Referring to FIG. 4, controller **50** includes a central processing unit (CPU) **51**, a memory **52**, an A/D converter **53**, a D/A converter **54**, a timer **56**, and a communication unit **57**. CPU **51**, memory **52**, A/D converter **53**, D/A converter **54**, timer **56**, and communication unit **57** can exchange data with each other via an internal bus **55**. Communication unit **57** is configured such that wireless communication or wired communication for exchanging data with the outside of controller **50** is performed.

Memory **52** is formed with a random access memory (RAM) and a read-only memory (ROM) for storing programs and data. Timer **56** is formed with an oscillator, for example, and generates a clock signal having a certain frequency for counting time.

A/D converter **53** and D/A converter **54** have a function as an input/output (I/O) circuit, and A/D converter **54** converts an analog voltage from the outside of controller **50** into a digital signal. For example, A/D converter **54** converts divided voltage V_{dv} (voltage dividing circuit **25**) and detected voltage V_c (current detector **90**) into digital data.

CPU **51** executes a computation process using a program and data stored in memory **52**, input voltage V_{in} detected from divided voltage V_{dv} , and coil current I_c obtained from detected voltage V_c . In the present embodiment, controller **50** performs duty control for controlling current supply to coil **110** by the on/off of switching element **80**.

FIG. 5 shows a waveform diagram for explaining the duty control.

Referring to FIG. 5, CPU **51** counts up count values C_{cyc} and C_{dt} every cycle of a clock signal by timer **56**.

Count value C_{cyc} is cleared to zero every time it reaches a count value C_{sw} corresponding to a switching period T_{sw} of switching element **80**. Count value C_{dt} starts to be counted up at the timing when count value C_{cyc} is cleared to zero. Further, count value C_{dt} is cleared to zero when reaching a count value C_{dr} in accordance with a set duty ratio DT . As described later, duty ratio DT is set within a range of $0 \leq DT \leq 1.0$, and count value C_{dr} is obtained by $C_{dr}=DT \cdot C_{sw}$.

Control signal S_{dv} makes a transition from “0” to “1” at the timing when count value C_{cyc} is cleared to zero. Further,

control signal S_{dv} makes a transition from “1” to “0” at the timing when count value C_{dt} is cleared to zero and is kept at “0” until the next timing when count value C_{cyc} is cleared to zero.

As a result, control signal S_{dv} makes a transition from “0” to “1” every switching period T_{sw} , and the ratio of the period of $S_{dv}="1"$ to switching period T_{sw} can be set in accordance with duty ratio DT . When $DT=1.0$, control signal S_{dv} is kept at “1”, and when $DT=0$, control signal S_{dv} is kept at “0”.

D/A converter **54** shown in FIG. 4 outputs control signal S_{dv} as a voltage pulse signal set to a logical low level (hereinafter simply referred to as “L level”) in a period of $S_{dv}="0"$ and set to a logical high level (hereinafter simply referred to as “H level”) in a period of $S_{dv}="1"$.

Referring to FIG. 1 again, driver **60** drives a voltage at the control electrode (gate voltage) of switching element **80** in accordance with control signal S_{dv} output from controller **50** (D/A converter **54**). Switching element **80** is thus controlled to turn on in a H level period of control signal S_{dv} and turn off in a L level period. Therefore, the on/off of switching element **80** is controlled in accordance with switching period T_{sw} in FIG. 5, and the ratio of the on period to switching period T_{sw} is controlled in accordance with duty ratio DT . Average current (corresponding to the mean value of coil current I_c) supplied to coil **110** by input voltage V_{in} thus can be controlled by duty ratio DT .

In the coil drive device of the electromagnetic contactor according to the first embodiment, the magnitude of coil current I_c is controlled by duty control of switching element **80** based on the magnitude of input voltage V_{in} .

FIG. 6 is a flowchart illustrating a process related to setting of a duty ratio in duty control of switching element **80**. The process shown in FIG. 6 is started when a close circuit command to bring electromagnetic contactor **200** into the closed state is input to controller **50**.

At step (hereinafter simply denoted as “S”) **110**, controller **50** sets an initial value of duty ratio DT . For example, $DT=0$ can be initially set. Further, at S120 to S150, controller **50** controls duty ratio DT in accordance with a parameter value indicating the magnitude of input voltage V_{in} so that coil current I_c does not become excessively large. Here, the effective value ($V_{in rms}$) of input voltage V_{in} is used as the parameter. Input voltage effective value $V_{in rms}$ is equivalent to the effective value of AC voltage V_{ac} from main power source **10**. In an example described below, input voltage effective value $V_{in rms}$ corresponds to an embodiment of “first parameter” but, for example, the mean value or the maximum value may be “first parameter” instead of the effective value.

Controller **50** samples divided voltage V_{dv} at S120 and performs effective value computation of input voltage V_{in} obtained from the sampling voltage at S130. For example, input voltage effective value $V_{in rms}$ can be calculated by extracting the maximum value of the sampling values (after V_{in} conversion) corresponding to half a cycle of AC voltage V_{ac} and multiplying the maximum value by $(\sqrt{2}/2)$. In doing so, in order to remove noise in the sampling voltage, the maximum value may be extracted from the sampling voltage (for a half cycle) passed through a lowpass filter.

Alternatively, at S130, the effective value may be calculated by computing the mean-square value of the sampling voltage (after V_{in} conversion). However, the effective value computation based on the maximum value extraction as described above can alleviate the operation load of CPU **51** and increase the calculation speed for the effective value.

If input voltage effective value $V_{in rms}$ is calculated (the determination is YES at S140), at S150, controller **50**

computes duty ratio DT according to the following equation (1) using a predetermined reference voltage V_r and the calculated input voltage effective value V_{inrms} . When $V_r \geq V_{inrms}$, DT=1.0 (maximum value) is set.

$$DT = V_r / V_{inrms} \quad (1)$$

In equation (1), for example, reference voltage V_r can be set to the nominal value (for example, 100 [V]) of the effective value of input voltage V_{in} corresponding to the nominal value (for example, effective value 100 [V]) of AC voltage V_{ac} from main power source 10. Reference voltage V_r corresponds to "reference value of the first parameter". Equation (1) is only an example, and the duty ratio can be set as desired as long as coil current I_c can be suppressed by setting duty ratio DT lower when $V_{inrms} > V_r$ than when $V_{inrms} \leq V_r$.

The process at S120 to S140 is repeatedly performed every sampling at S120. At S140, an initial value of input voltage effective value V_{inrms} can be calculated using the sampling value (after V_{in} conversion) at least for a half cycle of input voltage V_{ac} after the start of reading V_{dv} at S120. Subsequently, input voltage effective value V_{inrms} can be updated using the sampling value (after V_{in} conversion) a half cycle before, every time the half cycle elapses or multiple times in each subsequent half cycle. The determination at S140 is YES at the time of initial calculation of input voltage effective value V_{inrms} and at the timing of each subsequent update.

In a period until the initial calculation of input voltage effective value V_{inrms} and in a period other than each subsequent update timing, the determination at S140 is NO, and controller 50 keeps duty ratio DT at present at S160 and repeats the process of calculating input voltage effective value V_{inrms} at S120 to S140 in constant cycles as described above. As a result, duty ratio DT is adjusted to a value in accordance with the latest input voltage effective value V_{inrms} every time input voltage effective value V_{inrms} is calculated (updated).

Controller 50 continues the process at S120 to S150 to supply coil current I_c to coil 110 in accordance with duty ratio DT until an open circuit command for electromagnetic contactor 200 is input (the determination at S170 is NO). Generation of an electromagnetic force in accordance with coil current I_c keeps electromagnetic contactor 200 in the closed state.

On the other hand, if an open circuit command for electromagnetic contactor 200 is input (the determination at S170 is YES), controller 50 sets duty ratio DT=0 at S180. Thus, control signal S_{dv} is kept at L level and switching element 80 is fixed to the off state. As a result, because of coil current $I_c=0$, coil 110 does not generate an electromagnetic force, and therefore the biasing force by spring 140 (FIG. 2) opens electromagnetic contactor 200.

FIG. 7 is a simulation waveform diagram illustrating a first example of close circuit control in accordance with a close circuit command for electromagnetic contactor 200.

Referring to FIG. 7, at current feed start time t_s , operation switch 15 is turned on. Then, input voltage V_{in} obtained by full-wave rectification of AC voltage V_{ac} from main power source 10 is output from rectifier 20 to power supply line PL. In response, controller 50 is activated by a power supply voltage from control power source 30. Then, the process at S120 to S140 in FIG. 6 is performed.

At time t_x , input voltage effective value V_{inrms} is calculated from input voltage V_{in} for a half cycle of AC voltage V_{ac} (initial calculation). Until time t_x , duty ratio DT is kept at the initial value set at S110 in FIG. 6. As described above,

when duty ratio DT=0 is initially set, switching element 80 is kept in the off state until time t_x . Accordingly, start time t_0 of energization of coil 110 is equivalent to time t_x at which input voltage effective value V_{inrms} is calculated.

At energization start time t_0 , duty ratio DT is set using the calculated input voltage effective value V_{inrms} according to the above equation (1). In FIG. 7, an example in which $V_{inrms} > V_r$ and DT<1.0 is set is shown. After time t_x , duty ratio DT can also be changed every time input voltage effective value V_{inrms} is updated.

After energization start time t_0 , coil current I_c produces a magnetic flux in fixed core 120 to generate an electromagnetic force that attracts movable core 130 against the biasing force by spring 140. Once movable core 130 starts moving, the coil inductance value of coil 110 decreases with decrease of the gap between fixed core 120 and movable core 130, and coil current I_c increases.

At time t_a , fixed core 120 and movable core 130 come into contact with each other to complete the close circuit operation of electromagnetic contactor 200. Thereafter, there is no change in inductance value of coil 110, and coil current I_c increases or decreases in accordance with pulsation of input voltage V_{in} . The supply of coil current I_c is continued to keep electromagnetic contactor 200 in the closed state.

In the control example in FIG. 7, since coil current I_c can be controlled by duty ratio DT in accordance with input voltage effective value V_{inrms} from the start of energization, coil current I_c can be suppressed when input voltage V_{in} is higher than the nominal value. This control can prevent the electromagnetic force generated by coil 110 from becoming excessively large, thereby suppressing the impact when movable core 130 is attracted to fixed core 120 and thus suppressing the influence on the service life of electromagnetic contactor 200.

In the control example in FIG. 7, because of duty ratio DT=0 from the power feed start time t_s to time t_x at which input voltage effective value V_{inrms} is calculated, energization of coil 110 is awaited. Therefore, as described above, at S130 in FIG. 6, it is preferable that the time required for calculation of input voltage effective value V_{inrms} is reduced by the method that multiplies the maximum value extracted from the sampling values (after V_{in} conversion) for a half cycle of input voltage V_{in} by $(V/2)$.

FIG. 8 is a simulation waveform diagram illustrating a second example of close circuit control in accordance with a close circuit command for electromagnetic contactor 200.

Referring to FIG. 8, at power feed start time t_s , the supply of input voltage V_{in} obtained by full-wave rectification of AC voltage V_{ac} is started, and then controller 50 is activated by power supply voltage from control power source 30, in the same manner as in FIG. 7.

In the second example, at S110 in FIG. 6, duty ratio DT>0 is initially set. In the example in FIG. 8, duty ratio DT=1.0 is initially set, and the supply of coil current I_c can be started in response to generation of input voltage V_{in} with switching element 80 kept in the on state. That is, when DT>0 is initially set, start time t_0 of energization of coil 110 can be equivalent to power feed start time t_s at which operation switch 15 is turned on.

After energization start time t_0 , the process at S120 to S140 in FIG. 6 is performed concurrently with energization of coil 110 under duty ratio DT=1.0. At time t_x , input voltage effective value V_{inrms} is calculated (initial calculation), and then after time t_x , duty ratio DT is set according to the above equation (1) using the calculated input voltage effective value V_{inrms} . When $V_{inrms} > V_r$, as indicated by the example in FIG. 8, duty ratio DT decreases at time t_x .

After time t_x , duty ratio DT also changes every time input voltage effective value V_{inrms} is updated.

In the example in FIG. 8, after time t_x , electromagnetic contactor **200** is closed at time t_a , in the same manner as in FIG. 7. Therefore, since duty ratio DT is set in accordance with input voltage effective value V_{inrms} at time t_a , the impact of movable core **130** attracted to fixed core **120** due to excessive coil current I_c can be suppressed even when input voltage V_{in} is higher than the nominal value.

In the example in FIG. 8, when the required time from start time t_0 of energization of coil **110** to time t_a at which electromagnetic contactor **200** is closed is shorter than the time (time t_0 to t_x) required for computation of input voltage effective value V_{inrms} , duty control can be performed in accordance with input voltage effective value V_{inrms} without extending the required time from input of a close command to controller **50** to time t_a at which electromagnetic contactor **200** is closed. By doing so, the control of suppressing excessive coil current in the closed circuit of electromagnetic contactor **200** can be performed without influencing the entire sequence in a system including electromagnetic contactor **200** (for example, elevator cage control system).

By comparison, when the required time from start time t_0 of energization of coil **110** to when electromagnetic contactor **200** is closed (time t_a) is relatively short, it is preferable that energization of coil **110** is started with duty control after calculation of input voltage effective value V_{inrms} (after time t_x), in the same manner as the control example in FIG. 7, in terms of suppressing excessive coil current reliably.

In this way, in the electromagnetic contactor according to the first embodiment, even when AC voltage V_{ac} is higher than the nominal value, excessive coil current in the close circuit control can be suppressed by duty control using input voltage V_{in} sampled after the start of power-on. Thus, excessive coil current during close circuit control can be suppressed by simple control computation, rather than complicated and high-load control computation like the control of locus of coil current I_c after the start of energization as described in PTL 1. As a result, the control described above can be implemented using a relatively simple microcontroller without requiring high specifications, leading to lower cost of the coil drive device of the electromagnetic contactor.

Further, in the electromagnetic contactor according to the first embodiment, the closed circuit holding control after the close circuit control can also be performed by a simple control process.

FIG. 9 is a conceptual waveform diagram for explaining the closed circuit holding control by the coil drive device of the electromagnetic contactor according to the first embodiment.

Referring to FIG. 9, when electromagnetic contactor **200** is closed at time t_a after energization start time t_0 , after time t_a , it is necessary to generate an electromagnetic force for keeping movable core **130** attracted to fixed core **120** against the biasing force of spring **140**, as described above. However, after time t_a (closed state), there is almost no gap between fixed core **120** and movable core **130**, and therefore the generated electromagnetic force with respect to coil current I_c increases. On the other hand, before time t_a , although an electromagnetic force to move movable core **130** needs to be generated by coil **110**, the generated electromagnetic force with respect to coil current I_c is relatively small compared with after time t_a described above because there is a gap between fixed core **120** and movable

core **130**. Thus, current supplied to coil **110** after time t_a can be reduced compared with the value before time t_a .

Therefore, in the closed circuit holding control, compared with the close circuit control until time t_a , power consumption by coil current I_c can be suppressed by further reducing duty ratio DT . For example, a timer value T_m counted from energization start time t_0 is compared with a predetermined determination value T_{sh} , and after time t_b in which $T_m \geq T_{sh}$, the closed circuit holding control to reduce coil current I_c can be performed.

FIG. 10 is a flowchart illustrating a control process example for performing the closed circuit holding control shown in FIG. 9.

Referring to FIG. 10, if duty ratio DT is calculated at S150, the determination at S200 is YES, and controller **50** performs the process after S210 to perform the closed circuit holding control.

At S210, controller **50** compares timer value T_m at present with determination value T_{sh} . Determination value T_{sh} can be preset, based on an actual device test or the like, by converting a time length obtained by giving a margin to the actual value of the required time from the start of coil energization to when electromagnetic contactor **200** is closed (time length from time t_0 to t_a), into a timer value.

When $T_m \geq T_{sh}$ (the determination is YES at S210), controller **50** performs the closed circuit holding control at S220. Specifically, the value obtained by multiplying the calculation value ($DT = V_r/V_{inrms}$) at S150 by a control coefficient kh is set as duty ratio DT in the closed circuit holding control. Control coefficient kh is less than 1.0 and can be set to, for example, about 0.3 or can be preset in an actual device test or the like in consideration of the arrangement situation of electromagnetic contactor **200** (for example, the presence or absence of external vibration). In the closed circuit holding control, the maximum value of duty ratio DT is also kh .

On the other hand, in a period of $T_m < T_{sh}$ (the determination at S210 is NO), controller **50** proceeds to S230 without applying the closed circuit holding control. At S230, duty ratio DT calculated at S150 is kept.

As a result, as shown in FIG. 9, after time t_b when a predetermined time corresponding to determination value T_{sh} has elapsed since start time t_0 of energization of coil **110**, coil current I_c can be suppressed by the closed circuit holding control. As a result, power consumption for keeping electromagnetic contactor **200** in the closed state can be reduced by a simple control process based on the timer value.

Second Embodiment

There are individual differences in inductance value and resistance value among coils **110** due to variations in production. Because of such individual differences, coil current I_c may also vary for the same duty ratio DT . In a second embodiment, duty control that reflects individual differences of coil **110** will be described.

FIG. 11 is a block diagram illustrating a configuration of the coil drive device of the electromagnetic contactor according to the second embodiment.

Referring to FIG. 11, coil drive device **100** of the electromagnetic contactor according to the second embodiment is configured to communicate with a test device **101**. Specifically, controller **50** exchanges data with test device **101** using communication unit **57** (FIG. 4) through a communication channel **105** via wired communication or wireless communication. Test device **101** can be configured with, for

11

example, a computer (for example, personal computer) that can execute a program stored in advance.

Specifically, controller 50 transmits the locus of coil current I_c obtained from the detected voltage by current detector 90, that is, coil current data D_{IC} that is a combination of the time after the start of energization and a current value (I_c), to test device 101.

Test device 101 calculates an adjustment coefficient k_c for individual differences of coil 110, using AC voltage V_{AC} or input voltage V_{IN} and coil current data D_{IC} .

FIG. 12 is a flowchart illustrating a calculation process for adjustment coefficient k_c by test device 101. The process in FIG. 12 is performed, for example, in a test step of coil drive device 100.

Referring to FIG. 12, if operation switch 15 turns on to turn the power on (the determination at S310 is YES), test device 101 starts the process after S320.

Test device 101 receives and accumulates coil current data D_{IC} from controller 50 at S320 and accumulates the detected value of input voltage V_{IN} (or AC voltage V_{AC}) at S330.

Further, at S340, test device 101 extracts input voltage V_{IN} and coil current I_c in a predetermined evaluation period from the data accumulated at S320 and S330. For example, the evaluation period can be set as a half cycle or one cycle of AC voltage V_{AC} after time t_b in FIG. 9 in order to stably evaluate the inductance value, by way of example. The test period can be set as desired.

At S350, test device 101 calculates a coil current evaluation value I_{CTST} in the evaluation period. For example, coil current evaluation value I_{CTST} can be set as the mean value of coil current I_c in the evaluation period. Alternatively, coil current evaluation value I_{CTST} can be set by computing the effective value of the AC component of coil current I_c obtained by subtracting the above mean value from coil current I_c in the evaluation period. That is, coil current evaluation value I_{CTST} corresponds to "second parameter".

At S360, test device 101 calculates an input voltage evaluation value V_{INTST} in the evaluation period. For example, the effective value of AC voltage V_{AC} or input voltage V_{IN} in the evaluation period can be computed and set as input voltage evaluation value V_{INTST} . This input voltage evaluation value V_{INTST} corresponds to "first parameter".

Further, at S370, test device 101 calculates adjustment coefficient k_c according to the following equation (2), using predetermined input voltage reference characteristic value V_{IN}^* and coil current reference characteristic value I_c^* , and coil current evaluation value I_{CTST} and input voltage evaluation value V_{INTST} obtained at S350 and S360.

$$k_c = (V_{IN}^* / V_{INTST}) \cdot (I_c^* / I_{CTST}) \quad (2)$$

Coil current reference characteristic value I_c^* and input voltage reference characteristic value V_{IN}^* can be preset based on the actual values of input voltage V_{IN} and coil current I_c in the evaluation period obtained when coil current I_c is supplied by coil drive device 100 to coil 110 having characteristics serving as a reference. Input voltage reference characteristic value V_{IN}^* corresponds to "reference characteristic value of the first parameter", and coil current reference characteristic value I_c^* corresponds to "reference characteristic value of the second parameter".

Adjustment coefficient k_c is set to 1.0 when coil current reference characteristic value I_c^* is equal to coil current evaluation value I_{CTST} in the evaluation period. On the other hand, when $I_{CTST} > I_c^*$, $k_c < 1.0$ is set in accordance with the ratio between them, and when $I_c^* > I_{CTST}$, $k_c > 1.0$ is set in accordance with the ratio between them.

12

Further, adjustment coefficient k_c is corrected in accordance with the ratio between input voltage reference characteristic value V_{IN}^* and input voltage evaluation value V_{INTST} in the evaluation period. Specifically, in equation (2), the ratio between the value obtained by multiplying the calculated coil current evaluation value I_{CTST} by (V_{INTST} / V_{IN}^*) and coil current reference characteristic value I_c^* is determined. Thus, adjustment coefficient k_c can be calculated in accordance with the ratio between coil current reference characteristic value I_c^* and coil current evaluation value I_{CTST} after the influence of input voltage V_{IN} on coil current evaluation value I_{CTST} is eliminated.

At S380, test device 101 transmits adjustment coefficient k_c calculated at S350 to controller 50. Controller 50 stores the transmitted adjustment coefficient k_c into memory 52.

Controller 50 computes duty ratio DT according to the following equation (3), further using adjustment coefficient k_c stored in memory 52, instead of the above equation (1), at S150 in FIG. 6 described in the first embodiment.

$$DT = k_c \cdot (V_r / V_{INRMS}) \quad (3)$$

As a result, in the electromagnetic contactor according to the second embodiment, duty ratio DT is k_c times the calculation value in the first embodiment both in the close circuit control and the closed circuit holding control. As a result, differences in coil current I_c dependent on individual differences of coil 110 due to production variations and the like can be suppressed.

As a result, even when the inductance value of coil 110 is small and coil current I_c necessary for closing electromagnetic contactor 200 is larger than a reference, the close circuit control and the closed circuit holding control can be performed as appropriate. On the other hand, even when the inductance value of coil 110 is large and coil current I_c necessary for closing electromagnetic contactor 200 is smaller than a reference, the impact during circuit close and excessive power consumption during closed circuit holding due to excessive coil current I_c can be prevented.

Third Embodiment

In a third embodiment, control for reducing electromagnetic noise caused by the on/off control (duty control) of switching element 80 for controlling coil current I_c will be described.

As described in the first embodiment, control signal S_{DV} of switching element 80 is generated such that the ratio of the on period of switching element 80 to switching period T_{SW} is controlled, in accordance with duty ratio DT. Therefore, when switching period T_{SW} is fixed, switching frequency f_{SW} ($f_{SW} = 1 / T_{SW}$) of switching element 80 is fixed. Accordingly, the intensity of electromagnetic noise at a particular frequency may be increased. For example, when $T_{SW} = 100 \mu s$ is fixed, the intensity of electromagnetic noise at $f_{SW} = 10 \text{ kHz}$ may be increased.

In the third embodiment, control of the switching element for suppressing a peak intensity of electromagnetic noise will be described. In the switching control according to the third embodiment, count value C_{SW} corresponding to switching period T_{SW} shown in FIG. 5 is changed with the elapse of time, thereby preventing the switching frequency from being fixed.

FIG. 13 is a conceptual diagram illustrating an example of switching control according to the third embodiment.

Referring to FIG. 13, count value C_{SW} for a basic switching frequency f_0 (for example, $f_0 = 10 \text{ kHz}$) of switching element 80 is C_0 .

13

In the duty control by controller 50 explained with reference to FIG. 5, switching period T_{sw} (switching frequency f_0) can be changed by changing count value C_{sw} by ΔC . For example, it is preferable that switching frequency f_{sw} is gradually changed by limiting the range within $f_0 - \Delta f_0 \leq f_{sw} \leq f_0 + \Delta f_0$ such that the amount of change from switching frequency f_0 is within a certain amount.

In this case, count value C_{sw} to be compared with count value C_{cyc} is changed by ΔC within the limited range around C_0 from the minimum value C_a corresponding to the frequency $f_0 - \Delta f_0$ to the maximum value C_b corresponding to the frequency $f_0 + \Delta f_0$, whereby switching frequency f_{sw} can be gradually changed in the range of $f_0 - \Delta f_0 \leq f_{sw} \leq f_0 + \Delta f_0$. For example, $\Delta f_0 = 1$ [kHz] can be set for $f_0 = 10$ [kHz], and ΔC can be set to a count value to such a degree that the switching frequency changes by 100 [Hz]. In this way, setting the amount of change Δf_0 of the switching frequency and the amount of change ΔC_0 can prevent change of switching frequency f_{sw} from becoming too large and causing unstable control.

FIG. 14 is a conceptual diagram illustrating a distribution of electromagnetic noise intensity by switching control according to the third embodiment.

The dotted line in FIG. 14 depicts a distribution of electromagnetic noise intensity when switching frequency $f_{sw} = f_0$ is fixed. It is understood that the frequency of electromagnetic noise is concentrated on f_0 and therefore the intensity of electromagnetic noise at frequency f_0 is increased.

By comparison, the solid line in FIG. 14 depicts a distribution of electromagnetic noise intensity when the switching frequency change control shown in FIG. 13 is applied. It is understood that since switching frequency f_{sw} is gradually changed, the frequency region in which electromagnetic noise occurs is widened and consequently, the electromagnetic noise intensity at frequency f_0 becomes lower than the dotted line.

In this way, the switching control according to the third embodiment can reduce the peak intensity in the entire frequency region for electromagnetic noise produced by switching element 80. As a result, the coil current control described in the first and second embodiments can be implemented while a margin is ensured for harmonic regulation required for the power supply line.

The manner of change in count value C_{sw} , that is, switching period T_{sw} shown in FIG. 13 is illustrated by way of example, and the value of count value C_{sw} can be changed in any preferable manner in order to change switching frequency f_{sw} with the elapse of time.

Embodiments disclosed here should be understood as being illustrative rather than being limitative in all respects. The scope of the present invention is shown not in the foregoing description but in the claims, and it is intended that all modifications that come within the meaning and range of equivalence to the claims are embraced here.

The invention claimed is:

1. An electromagnetic contactor comprising:
a first contact;
a second contact;
a mechanism to generate a biasing force for opening the first and second contacts;
an operation coil to generate an electromagnetic force for bringing the first and second contacts into contact with each other against the biasing force; and
a coil drive device to supply current for generating the electromagnetic force to the operation coil,
the coil drive device including
a rectifier to output, to a power supply line, an input voltage obtained by full-wave rectification of an AC voltage supplied from an AC power source,
a switching element connected to the power supply line in series with the operation coil,
a voltage detector to detect the input voltage, and
a controller to control on and off of the switching element, wherein

the controller controls on and off of the switching element so as to control a duty ratio that is a ratio of an on period of the switching element in a switching period shorter than one cycle of the AC voltage, and controls the duty ratio in accordance with a value of a first parameter indicating a magnitude of the input voltage that is calculated using a detected value of the voltage detector, in at least a partial period after start of energization of the operation coil in response to a close command for the electromagnetic contactor, and

when a calculation value of the first parameter is larger than a predetermined reference value, the duty ratio is set to a value lower than when the calculation value is equal to or smaller than the reference value, wherein the reference value is set to a value of the first parameter corresponding to a nominal value of the AC voltage, and

when the calculation value of the first parameter is larger than the reference value, the controller sets the duty ratio in accordance with a value obtained by dividing the reference value by the calculation value.

2. An electromagnetic contactor comprising:
a first contact;
a second contact;
a mechanism to generate a biasing force for opening the first and second contacts;
an operation coil to generate an electromagnetic force for bringing the first and second contacts into contact with each other against the biasing force; and
a coil drive device to supply current for generating the electromagnetic force to the operation coil,
the coil drive device including
a rectifier to output, to a power supply line, an input voltage obtained by full-wave rectification of an AC voltage supplied from an AC power source,

15

a switching element connected to the power supply line in series with the operation coil,
 a voltage detector to detect the input voltage, and
 a controller to control on and off of the switching element, wherein
 the controller controls on and off of the switching element so as to control a duty ratio that is a ratio of an on period of the switching element in a switching period shorter than one cycle of the AC voltage, and controls the duty ratio in accordance with a value of a first parameter indicating a magnitude of the input voltage that is calculated using a detected value of the voltage detector, in at least a partial period after start of energization of the operation coil in response to a close command for the electromagnetic contactor, and
 when a calculation value of the first parameter is larger than a predetermined reference value, the duty ratio is set to a value lower than when the calculation value is equal to or smaller than the reference value, wherein the controller determines the duty ratio of the switching element by multiplying an adjustment coefficient that reflects individual differences of the operation coil.

3. The electromagnetic contactor according to claim 2, wherein the reference value is set to a value of the first parameter corresponding to a nominal value of the AC voltage, and

when the calculation value of the first parameter is larger than the reference value, the controller sets the duty ratio in accordance with a value obtained by dividing the reference value by the calculation value.

4. The electromagnetic contactor according to claim 3, wherein

when the calculation value is equal to or smaller than the reference value, the controller sets the duty ratio to 1.

5. The electromagnetic contactor according to claim 1, wherein

when the calculation value is equal to or smaller than the reference value, the controller sets the duty ratio to 1.

6. The electromagnetic contactor according to claim 1, wherein

the controller determines the duty ratio of the switching element by multiplying an adjustment coefficient that reflects individual differences of the operation coil.

7. The electromagnetic contactor according to claim 1, further comprising a current detector to detect coil current flowing through the operation coil, wherein

the adjustment coefficient is calculated using a value of a second parameter indicating a magnitude of the coil current that is calculated using a detected value of the

16

current detector during energization of the operation coil, a value of the first parameter calculated using the detected value of the voltage detector during the energization, and reference characteristic values of the first and second parameters obtained in advance during energization of the operation coil having characteristics serving as a reference.

8. The electromagnetic contactor according to claim 1, wherein the controller sets the duty ratio to 0 at start of supply of the AC voltage to the rectifier to await energization of the operation coil, performs calculation of the first parameter using the detected value of the voltage detector, and after acquiring a calculation value of the first parameter, starts energization of the operation coil with control of the duty ratio in accordance with the calculation value.

9. The electromagnetic contactor according to claim 1, wherein the controller sets the duty ratio larger than 0 from start of supply of the AC voltage to the rectifier to start energization of the operation coil, performs calculation of the first parameter using the detected value of the voltage detector, and after acquiring a calculation value of the first parameter, controls the duty ratio in accordance with the calculation value.

10. The electromagnetic contactor according to claim 1, wherein

when a predetermined determination time has elapsed since start of energization of the operation coil, the controller sets the duty ratio lower than before elapse of the determination time, and

the determination time is set to be longer than a required time from the start of energization to when the electromagnetic contactor is brought into a closed state by contact between the first and second contacts.

11. The electromagnetic contactor according to claim 1, wherein

the first parameter is an effective value, and

the controller extracts a maximum value of the detected value of the input voltage by the voltage detector in a period equal to or longer than a half cycle of the AC voltage and calculates the effective value by multiplying the maximum value by a predetermined coefficient.

12. The electromagnetic contactor according to claim 1, wherein the controller changes the switching period of the switching element with elapse of time, in control of the duty ratio.
